UNITED STATES PATENT OFFICE

CAROLINE G. HUMPHREYS, OF FOREST HILLS, NEW YORK

DESIGN FOR A BOTTLE

Application filed January 12, 1932. Serial No. 42,461. Term of patent 14 years.

To all whom it may concern:

Be it known that I, CAROLINE G. HUMPHREYS, a citizen of the United States of America, residing at No. 215 Greenway South, Forest Hills, in the county of Queens and State of New York, have invented a new, original, and ornamental Design for a Bottle, of which the following is a specification, reference being had to the accompanying drawings, forming a part thereof, and showing, in—

Fig. 1 a front view, in Fig. 2 a side view and in Fig. 3 a top view of the bottle embodying my design.

I claim:

The ornamental design for a bottle substantially as shown.

CAROLINE G. HUMPHREYS.
